No. 285

Fig. 1

Isa C. Brownell. Design for door. October 22, 1902.

Design for door

Asa C. Brownell of Providence R. I.

Letters Patent No. 285. Dated May 28, 1850.

The Schedule referred to in these Letters Patent and making part of the same.

To all Persons to whom these Presents shall come:

Be it known that I, Asa C. Brownell of Providence in the County of Providence and State of Rhode Island have invented or produced a new and useful design for the side plate of a Cooking Stove, and I do hereby declare, that the said new design is fully described and represented in the following specification and accompanying drawings, to which reference is hereinafter made.

Of said drawings, Fig. 1. represents an elevation of my new design on the said side plate, and Fig. 2. is a horizontal section taken in the plane of the line A. B. Fig. 1.

The said design consists, firstly of the double gothic arch a a - a a formed on the panel b b of the main door, the sides of said arches being formed of clustered ribs c, c. c - c, c. c &c. in alto relief as shown in Fig. 1 & 2, the door being surrounded by the enriched moulding d. d. d. d; secondarily, of the square panel e e, with its surrounding moulding o o o o and gothic arches with clustered raised ribs on the sides of said arch; said panel being directly over the ash fit door, which is similarly ornamented with the arch g g and moulding h h h h; thirdly, of the elongated horizontal panels i i i - k k k extending along the top and bottom of the plate, with mouldings in alto relief, and connected by the similar vertical panel n n n at the rear of the plate, and lastly of the trapezoidal panel l l l, under the edge where the hearth plate rests; said panel being surrounded by the moulding m m m m.

What I claim as my invention in the said design and desire to have secured to me by Letters Patent is the combination of the elongated horizontal panels i i i - k k k and vertical connecting panel n n n, all having mouldings in alto relief, with the several doors and panels having gothic arches with clustered raised ribs on their sides, and mouldings as above specified and shown in the drawings.
